UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

SIDE BEARING.

Application filed July 9, 1923. Serial No. 650,207.

To all whom it may concern:

Be it known that I, JOHN F. O'CONNOR, a citizen of the United States, residing at Chicago, in the county of Cook and State of Illinois, have invented a certain new and useful Improvement in Side Bearings, of which the following is a full, clear, concise, and exact description, reference being had to the accompanying drawings, forming a part of this specification.

This invention relates to improvements in side bearings.

One object of the invention is to provide a side bearing particularly adapted for rail-way cars wherein the anti-friction element is automatically centered under the influence of gravity after each actuation and upon removal of the pressure.

More specifically, the object of my invention is to provide a side bearing having gravity weights so arranged that, when the anti-friction element proper is moved to either side of central normal position, the gravity weights will be elevated and thereby moved to a position to automatically insure the return of the anti-friction element when the load is removed.

In the drawing, Figure 1 is a vertical, sectional view taken through the ends of a body and truck bolster of a car showing my improvements in connection therewith. Figure 2 is a vertical, sectional view corresponding substantially to the line 2—2 of Figure 1. And Figure 3 is a top plan view of the side bearing proper shown in Figure 1.

In said drawing, 10 indicates the upper portion of a truck bolster and 11 the underside of an opposed body bolster of a rail-way car. As shown, the improved bearing is attached to the truck bolster and comprises, broadly, a retaining or housing casting A; an anti-friction element proper B; a pair of weight blocks C—C; and a retaining pin for the anti-friction element D.

The housing or retaining member or base casting A is preferably in the form of a hollow box having an integral bottom wall 12, vertical end walls 13—13 and vertical side walls 14—14, the casting being open at the top as clearly shown in Figures 1 and 2. The casting is provided with suitably perforated flanges 15 by which the casting is adapted to be secured to the bolster, as by the rivets 16. Preferably, an inserted wear

plate 17 is employed in the bottom of the housing, said plate being inserted through suitable openings 18 in the end walls of the housing and secured in place by rivets 19, the bottom of which are made flush with the lower surface of the housing.

The anti-friction element B, as shown, is in the form of a cylindrical roller and is centrally perforated to accommodate the retaining pin D which is loosely passed therethrough. Said pin D is applied through openings 20 in the side walls 14 before the plate 17 is inserted. With this construction, it will be evident that the parts are held in assembled relation after the plate 17 is inserted, the ends of the pin D traveling back and forth in horizontal grooves 21 formed on the inner side of the side walls 14 and preventing the roller from being lifted out. Said pin also extends through recesses in the weight blocks C so that the latter are also retained, as will be obvious.

The weight blocks C are of like construction, the same being located one at each end of the roller B. Each of said weight blocks C is in the form of a relatively thick plate of rectangular outline and of such a height that, normally, the upper edge 22 thereof is disposed below the upper edge of the housing and said edge 22 when the weight blocks are in their most elevated position, will always be below the upper contacting portion of the roller. Each weight block C is provided with an elongated recess 23, having a lower edge defined by an arcuate convex surface 24, curved end surfaces 25—25 and an upper edge defined by two end flat surfaces 26—26, and two intermediate flat surfaces 27—27. The flat surfaces 27 are inclined upwardly from the horizontal at a comparatively acute angle with the horizontal, whereas the other two surfaces 26 are inclined upwardly at a much greater angle with respect to the horizontal. Each set of surfaces 26 and 27 intersect or merge at a point, as indicated approximately at 28. It will also be noted from an inspection of Figures 1 and 3 that the weight blocks C are restrained from longitudinal movement with respect to the housing A, or, stated in another manner, are confined to a vertical movement only. The edges of the weight blocks C may be cut away as indicated at 29, near their centers to permit foreign matter to be

100
105
110

washed out from within the housing, the side walls of the latter being similarly apertured as indicated at 30.

The roller B carries two diametrically disposed pins 31 and 32, said pins being in horizontal alinement when the roller is in its central normal position shown in Figure 1. The ends of said pins 31 and 32 are projected beyond the ends of the roller and 10 each projecting end of each pin 31 and 32 carries an anti-friction little roller 31' and 32', respectively. Said little anti-friction rollers 31' and 32' are disposed within the recesses 23 of the weight blocks C and, in 15 normal position of the parts, will engage the upper edges of said recesses approximately at the points 28, as shown in Figure 1 so that, when the weight blocks C are in their lowermost position, the roller will be there- 20 by held in central position. When the roller is actuated to either side of central position, as for instance, toward the left as shown by the dotted lines in Figure 1, the two left- 25 hand little rollers 32' will travel in a down- ward direction to the position indicated by the dotted lines 32², while at the same time the other little anti-friction rollers 31' will be elevated until they reach the position shown by 31² in Figure 1. The elevation of 30 the rollers 31' results in a corresponding elevation of the weight blocks C which, as heretofore stated, are confined to a vertical movement. Consequently, when the load is taken from the anti-friction roller, the 35 weight blocks C will automatically bear down upon the little anti-friction rollers 31', causing the latter to induce a return rolling action of the anti-friction roller, until the parts again assume their central position. 40 In this connection it will be observed that, in returning the anti-friction roller to central position, there is no danger of overthrow since both sets of anti-friction rollers 31' and 32' will be engaged with the weight 45 blocks C at points equidistant from the center thereof.

All of the parts are held in assembled relation in the manner heretofore described and from the preceding description, it will be 50 seen that I insure automatic return of the anti-friction element to central position, without the aid of springs or other delicate parts likely to get out of order. The arrangement is simple, the parts may be made 55 at comparatively small expense, and the roller is of rugged and substantial construction.

I have herein shown and described what I now consider the preferred manner of carrying out my invention, but the same is merely illustrative and I contemplate all changes and modifications that come within the scope of the claims appended hereto.

I claim:

65 1. In a side bearing, the combination

with a retaining member adapted to be secured to a bolster; of an anti-friction element adapted to roll back and forth within said retaining member; weight blocks mounted in said retaining member and confined substantially to a movement at right angles to the line of bodily movement of the anti-friction element; and co-operating means on said anti-friction element and weight blocks to effect elevation of the latter when the anti-friction element is moved to either side of central position, said weight blocks being then effective to return said element to central position when the load is removed. 70 75 80

2. In a side bearing, the combination with a hollow housing adapted to be secured to a bolster; of an anti-friction element adapted to roll back and forth within said housing; a weight block mounted within said housing and guided by the latter in a vertical direction; and co-operating means on said roller and block automatically operable to elevate said block when the element is rolled to either side of central position. 85 90

3. In a side bearing, the combination with a hollow housing adapted to be secured to a bolster; of an anti-friction element disposed within said housing and adapted to roll back and forth therein; of a pair of weight blocks, one at each end of said roller and interposed between the ends of the latter and walls of the housing, said weight blocks being confined to a vertical movement with respect to the housing; and co-operating means on said element and weight blocks for effecting elevation of the latter when said element is rolled to either side of central position. 95 100

4. In a side bearing, the combination with a hollow housing adapted to be secured to a bolster; of an anti-friction element disposed within said housing and adapted to roll back and forth therein; of a pair of weight blocks, one at each end of said roller and interposed between the ends of the latter and walls of the housing, said weight blocks being confined to a vertical movement with respect to the housing; and co-operating means on said element and weight blocks for effecting elevation of the latter when said element is rolled to either side of central position, said means including eccentrically disposed projections from the ends of the roller and recesses within the blocks within which said projections are received. 105 110 115 120

5. In a side bearing, the combination with a hollow housing adapted to be secured to a bolster; of an anti-friction roller mounted within said housing and adapted to roll back and forth therein; weight blocks, one at each end of the roller and disposed between the latter and adjacent walls of the housing, said blocks being confined substan- 125 130

tially to a vertical movement with respect to the housing, each of said blocks having an elongated recess therein; and diametrically disposed projections from the ends 5 of said roller and disposed within said recesses and by which the weight blocks are elevated when the roller moves to either side of central position.

6. In a side bearing, the combination 10 with a hollow box-like housing adapted to be secured to a truck bolster; of an anti-friction roller mounted within said housing and adapted to roll back and forth therein; a pair of weight blocks, one at each end of 15 the roller and interposed between the ends of the latter and side walls of the housing, each of said blocks having an elongated recess therein; and diametrically and eccentrically disposed projections at each end of 20 the roller disposed within said recesses and normally engaging the upper edges of said recesses whereby, when the roller is moved to either side of central position, the blocks are elevated in a vertical direction and automatically serve to return the roller to central normal position when the load is removed.

7. In a side bearing, the combination with 25 a housing adapted to be secured to a bolster, said housing having side walls; of an anti-friction roller adapted to roll back and forth within said housing; a pair of weight blocks, one at each end of the roller and interposed between the ends of the roller and 30 said side walls of the housing, each block having an elongated recess therein; means

confining movement of said weight blocks to a vertical direction with respect to the housing; and diametrically and eccentrically disposed smaller anti-friction rollers carried by each end of said first named anti-friction roller, said smaller anti-friction rollers working within said recesses of the weight blocks.

8. In a side bearing, the combination with 45 a casing; of a counter-weighted roller mounted therein; and a vertically sliding weight coacting with said roller to effect return of the latter to normal position.

9. In a side bearing, the combination with 50 a casing; of a roller within said casing; a sliding counter-weight within said casing guided for vertical movement only; and coacting means on said roller and weight for maintaining a predetermined relation 55 between said roller and casing.

10. In a side bearing, the combination with 60 a casing; of a roller within said casing, said roller being provided with eccentric lugs; of a pair of sliding counter-weights within said casing, said counter-weights being provided with guideways for receiving said lugs; and means for guiding the counter-weights for movement in a predetermined path.

In witness that I claim the foregoing I have hereunto subscribed my name this 6th day of July 1923.

JOHN F. O'CONNOR.
